UNITED STATES PATENT OFFICE.

VAN T. WYCISLO, OF CHICAGO, ILLINOIS.

CENTERING-GAGE.

1,249,584.

Specification of Letters Patent.

Patented Dec. 11, 1917.

Application filed March 22, 1916. Serial No. 85,772.

To all whom it may concern:

Be it known that I, VAN T. WYCISLO, a citizen of the United States, and resident of Chicago, in the county of Cook and State of Illinois, have invented certain new and useful Improvements in Centering-Gages, of which the following is a specification.

The present invention relates to improvements in centering devices for the proper presentation of work to the work-performing element, and it is primarily concerned with a gage of this nature for use with drill-presses and milling cutters to expedite the drilling of holes and the cutting of key 15 races or spline grooves in material of varying shapes.

The main and primary object of the present invention is the provision of a centering gage having but a minimum number of parts, the relation of which is such that the gage may be expeditiously applied to and removed from a tool while the latter is in the machine, and when so applied will afford such a presentation to the tool of the work 25 to be centered as to preclude necessity of any measurement to determine the accuracy of such centering.

The invention further aims to provide a centering gage having provision to adapt 30 the same for use with various sizes of stock and means to enable its speedy adjustment for application thereto in accordance with the dimensions of the particular piece to be centered.

Furthermore, the invention also seeks to provide a gage of this nature, the construction of which is such as to permit its use for straight-line measurement.

With these general objects in view, and others which will appear as the nature of the improvement is better understood, the invention consists substantially in the novel construction, combination and arrangement of parts hereinafter fully described, illustrated in the accompanying drawings, and finally pointed out in the appended claims.

In the drawings,

Figure 1 is a side elevation of a centering gage constructed in accordance with the present invention and shown as applied to a drill, the view also illustrating the manner in which the stock is centered by the gage with respect to the drill;

Fig. 2 is a sectional plan view on the line 55 2-2 of Fig. 1;

Fig. 3 is a vertical sectional view of the

gage taken on a line approximately midway of the gage members.

Referring in detail to the accompanying drawings, the numerals 1 and 2 designate the members of the herein described gage. Each of these members includes a vertically extending shank 3, which shanks lie substantially parallel to each other so that the same may readily embrace the tool to which the centering gage is applied. The inner opposing faces of these shanks 3 are plane, and each is provided with a vertically extending groove 4 in which the tool to which the gage is applied is seated. The shanks 3, therefore, embrace the tool and the parallel relation of the members is thereby assured. Obviously, the grooves 4 extend throughout the length of the inner faces of the shanks 3. At the lower end of each of the shanks 3 is arranged an angularly-disposed contact finger 5, these fingers, when the members are assembled, extending in divergent or flaring relation with respect to each other at an angle of ninety degrees. This relation of the fingers 5 so positions them with respect to the work to be centered that the fingers will contact with the work at two points, as clearly illustrated in Fig. 1. It will also be observed that the work-engaging faces of the fingers 5 are disposed in angular relation to the tool-engaging faces of the shanks 3, so that in the assembled relation of the members 1 and 2 the tool-engaging faces lie parallel, and the work-engaging faces extend in divergent relation with respect to the tool-engaging faces.

Mounted on the member 1 and extending at right angles to the shank 3 thereof is a supporting arm 6, which arm is connected to the member 1 through the medium of a screw 7, or its equivalent. The supporting arm 6 fits within and is received by an elongated guide loop 8, carried by the shank 3 of the member 2. The supporting arm 6 is provided with an elongated slot 9 to receive a clamping bolt 10, the head of which is seated in a countersink 11 formed in the shank of the member 2, and the screw threaded end of said bolt passes through the guide loop 8 and has mounted thereon a winged nut 12 by which pressure may be exerted on the parts to hold the shanks 3 in adjusted relation with respect to each other.

In order that the supporting arm 6 may be held at right angles to the shank of the member 1, said shank is provided with a

pair of parallel ribs 13, between which the arm 6 is arranged. The space between these ribs is just sufficient to snugly receive the arm 6, and when the latter is fastened 5 to the member 1 by the screw 7, said arm will be held in rigid relation to the member 1.

The supporting arm 6 is also provided with graduations 14, based upon proper 10 scale measurements, whereby to determine with ease the extent of movement of the jaws of the members 1 and 2 with respect to each other, thereby to facilitate application of the gage to known sizes of drills or 15 other tools with which the same is to be used.

In using the present invention, the nut 12 is loosened to relieve the pressure on the supporting arm 6, whereupon the members 1 and 2 may be readily separated or moved 20 away from each other the required distance to permit application of the gage to the tool. If the latter be a drill, as illustrated in Fig. 1 of the drawing, the members are arranged at opposite sides of the same and 25 pushed together, the drill seating itself in the vertical grooves 4. The nut 12 is now tightened, thereby binding the parts, and this effectually holds the members 1 and 2 on the drill. The point of the drill is, of 30 course, permitted to project the required extent below the lower ends of the shanks 3. The work is now presented to the tool and brought into contact with the inner face of each of the contact fingers 5, as illustrated 35 in Fig. 1, and with the gage rigidly held on the tool it is obvious that when this contact with the fingers 5 is made, and the stock is incapable of any lateral movement with respect to the gage, the work becomes 40 centered beneath the tool. The gage is then removed from the tool, and if this be a drill the opening or hole is bored to the required extent; the drill removed from the work, the latter moved to a new position beneath the 45 drill, whereupon the gage may be again applied to the drill and the work centered in the manner just described.

As shown in the drawings, the work or stock is of cylindrical shape, as a shaft. If 50 it were desired to form in the shaft key races or spline grooves, it is evident that the gage would be applied to the milling cutter in the same manner as applied to a drill. Should the work or stock have any 55 other shape than that of a shaft, such as a square bar, it would also be seen that the same method of centering would be followed in such particular. The corners of the bar would be brought into contact with the inner faces of the fingers 5, and when so contacted with these fingers the bar would be 60 centered with respect to the tool which is to operate thereon.

As the contact fingers 5 are arranged at 65 an angle of ninety degrees to each other, it

will be seen that when the shanks 3 are closed together and brought into contact the inner faces of the fingers 5 are at right angles to each other. In this relation the gage may be used for straight-line measurement, and likewise for determining the accuracy of right angles.

It will be understood that the invention may be used also for centering the ends of stock. Such use contemplates only the different presentation of the work, the gage being applied to the tool in the same manner as when the side of the stock is presented.

Having thus described the invention, what is claimed as new, and desired to be secured 80 by Letters Patent is:

1. A centering gage, comprising a plurality of relatively-adjustable members including tool-embracing elements, work-contacting elements carried by said members 85 for centering the work with respect to the tool embraced by the members, and means for effecting relative adjustment of the members.

2. A centering gage, comprising a plurality of relatively adjustable members including substantially parallel tool-embracing elements, work-contacting elements carried by said members for centering the work with respect to the tool embraced by the 95 members, said work-contacting elements being disposed in angular relation to the tool-embracing elements, and means for effecting relative adjustment of the members.

3. A centering gage, comprising a plurality of members provided with parallel shanks for embracing a tool, a contact finger carried by each shank and disposed at an angle thereto, whereby said fingers extend in divergent relation to said shanks, and means 100 for effecting relative adjustment of the members.

4. A centering gage, comprising a plurality of members provided with parallel shanks for embracing a tool, the inner faces 110 of said shanks having grooves for the reception of said tool, a contact finger carried by each shank and disposed at an angle thereto, whereby said fingers extend in divergent relation to said shanks, and means for effecting relative adjustment of the members.

5. A centering gage, comprising a plurality of members including tool-embracing elements, work-contacting elements carried by said members for centering the work with 120 respect to the tool embraced by the members, a supporting arm carried by one of said members and having a slidabile connection with the other member, and means for holding the latter in adjusted position on 125 said arm.

6. A centering gage, comprising a plurality of members including substantially parallel tool-embracing elements, work-contacting elements carried by said members 130

for centering the work with respect to the tool embraced by the members, a supporting arm carried by one of the tool-embracing elements and extending at right angles thereto, said arm having a slidable connection with the other member, and means for holding the latter in adjusted position on said arm.

7. A centering gage, comprising a plurality of members including substantially parallel tool-embracing elements, work-contacting elements carried by said members for centering the work with respect to the tool embraced by the members, said work-contacting elements being divergently arranged with respect to each other, a supporting arm carried by one of the tool-embracing elements, the other tool-embracing element having a slidable connection 20 with said arm, and means for locking the members in adjusted relation.

8. A centering gage, comprising a plurality of members including substantially parallel tool-embracing elements, work-contacting elements carried by said members and arranged in angular relation thereto for centering the work with respect to the tool embraced by the members, a supporting arm carried by one of said members and provided with an elongated slot, the other member being slidably mounted upon said supporting arm, and clamping means extending through the slot of said supporting arm and the member carried by the latter, whereby 35 to lock said member on said arm and hold the members in adjusted relation to each other.

9. A centering gage, comprising a plurality of members including substantially parallel tool-embracing shanks, a contact finger carried by each of said shanks, said fingers being arranged in divergent relation to each other, whereby to contact the work and center the latter with respect to the tool 45 embraced by said shanks, a supporting arm carried by the shank of one of said members, the shank of the other member being slidably mounted on said arm, and means for

locking the members in adjusted relation to each other.

10. A centering gage, comprising a plurality of members including substantially parallel tool-embracing shanks, a contact finger carried by each of said shanks, said fingers being arranged in divergent relation to each other, whereby to center the work with respect to the tool embraced by the shanks, a supporting arm carried by the shank of one of said members and extending at right angles thereto, said arm being provided with an elongated slot, the shank of the other member being slidably mounted on said arm, and a clamping bolt passing through the slot of said supporting arm and the shank of the member supported by said arm for binding said member on the supporting arm and holding the members in adjusted relation with respect to each other.

11. A centering gage, comprising a plurality of members adapted to embrace a tool and having parallel tool-engaging faces, a contact finger carried by each member and having a work-engaging face disposed at an angle to the tool-engaging face thereof, the work-engaging faces of said members extending in divergent relation with respect to each other when said members are assembled, and means for effecting relative adjustment of the members.

12. A centering gage, comprising a plurality of members each of which is provided with a tool-engaging face and a work-engaging face disposed in angular relation to each other, the tool-engaging faces lying parallel and the work-engaging faces extending in divergent relation with respect to the tool-engaging faces when said members are assembled, and means for effecting relative adjustment of the members.

Signed at Chicago, Illinois, this 18th day 90 of March, 1916.

VAN T. WYCISLO.
